UNITED STATES PATENT OFFICE.

EDWARD H. DEWES, OF ST. LOUIS, MISSOURI.

WAGON-BODY CLAMP.

SPECIFICATION forming part of Letters Patent No. 761,456, dated May 31, 1904.

Application filed November 4, 1901. Serial No. 81,110. (No model.)

To all whom it may concern:

Be it known that I, EDWARD H. DEWES, a citizen of the United States, residing at St. Louis, in the State of Missouri, have invented 5 certain new and useful Improvements in Wagon-Body Clamps, of which the following is a specification, reference being had therein to the accompanying drawings.

This invention relates to improvements in 10 body-clamps; and it consists in the novel arrangement, construction, and combination of parts, as will be more fully hereinafter described, and set forth in the claim.

The object of this invention is to provide a 15 device to be secured to the sides of a wagon-body, especially the farm-wagon type, and is for the purpose to tightly clamp the side-boards to the body proper.

A further object is its simplicity and rapid 20 manner of manipulation and adjustment for the various pressure desired.

Figure 1 is a front view of my complete invention shown in its operative position. Fig. 2 is a side view of the same, showing its released position by dotted lines. Fig. 3 is a 25 detail vertical sectional view of the upper socket member. Fig. 4 is a detail vertical sectional view of the lower member, some of its supported parts being broken away. Fig. 30 5 is a detail view, with a part broken away, of the pressure-bolt made use of in connection with my invention. Fig. 6 is a detail plan view of the nut used in connection with my invention.

35 In the construction of the device as shown I provide two suitable castings 1 and 2, all parts being preferably malleable and are secured to the wagon-body and side-board by screws or like devices, as found most substantial by the trade. The casting 1 is secured to the side-board 3 and the casting 2 to the wagon-body 4. Integral with the casting 2 are 40 ears or projecting lugs 5, each provided with

trunnions 6, on which is pivotally secured a toggle-lever 7, having apertures 8 for supporting the nut 9 and acting as bearings for its integral trunnions 10.

The nut is provided with a threaded aperture through which the pressure-bolt 11 is passed and therein adjusted, the head of said bolt being preferably T-shaped, as shown. It will be observed by referring to the side view of the drawings that the aperture 8 is arranged out of vertical alinement with the trunnions 6. The purpose of this is to provide 55 a straight leverage upon the bolt, so that when the same has passed the center it will remain in the tightened position, as shown.

The casting 1 has a socket 12, in which the head of the bolt rests, and is sufficiently strong 60 to withstand the pulling pressure.

Much difficulty heretofore has been found by farmers in finding a means whereby the side-board could be tightly fitted upon the wagon-body. As a result the grain would be 65 lost by falling through the open joint. By this device a perfect tight fit can be had and can be regulated by the adjustment of the bolt in the nut. Its operation is simple and efficient and its construction cheap and durable. 70

I claim—

A wagon-body clamp comprising castings 1 and 2, a pocket formed on casting 1, integral ears formed on casting 2, a toggle-lever 7 pivoted to said ears, a nut carried by said toggle-lever, a T-shaped bolt 11 resting in the pocket of casting 1, and adjusted in nut 9, for the purpose of drawing the wagon-body together, substantially as specified.

In testimony whereof I affix my signature in 80 presence of two witnesses.

EDWARD H. DEWES.
